UNITED STATES PATENT OFFICE.

REGINALD J. THURLOW, OF ALEXANDER, NORTH DAKOTA.

TYPE-WRITING MACHINE.

1,233,936.

Specification of Letters Patent. Patented July 17, 1917.

Application filed November 21, 1916. Serial No. 132,629.

To all whom it may concern:

Be it known that I, REGINALD J. THURLOW, a citizen of the United States, residing at Alexander, in the county of McKenzie 5 and State of North Dakota, have invented new and useful Improvements in Type-Writing Machines, of which the following is a specification.

This invention relates to typewriting machines, and it has for its object to produce an attachment of simple and improved construction including a motor whereby the operator will be relieved of a large proportion of the strain and stress of operating the machine, particularly as regards the striking of the keys and the return of the carriage and advancing of the paper.

A further object of the invention is to produce a simple and improved device which 20 may be utilized as an attachment to a conventional typewriting machine or which may be permanently installed or built into such machine, the same including a keyboard corresponding to the keyboard of the typewriting 25 machine and having a corresponding set of keys, by the manipulation of which mechanism will be set in motion whereby the keys of the typewriter will be actuated.

A further object of the invention is to 30 produce a simple and improved device of the character described having actuating keys by the manipulation of which the keys of the typewriter will be mechanically actuated not merely once, but the operation being repeated as long as the key of the attachment 35 is maintained in a depressed position, thus enabling any character to be depressed as many times as may be desired without manipulating the actuating attachment but once.

A further object of the invention is to produce a simple and improved device whereby, by the manipulation of a single key or lever or the keyboard, mechanism 45 will be set in motion whereby the carriage will be returned and the platen rotated to advance the paper the desired distance.

A further object of the invention is to produce a simple and improved device of 50 the character described including a simple and effective means for actuating the shift key of the typewriter.

With these and other ends in view which will readily appear as the nature of the invention is better understood, the same consists in the improved construction and novel arrangement and combination of parts which will be hereinafter fully described and particularly pointed out in the claims.

In the accompanying drawings has been 55 illustrated a simple and preferred form of the invention, it being, however, understood, that no limitation is necessarily made to the precise structural details therein exhibited, but that changes, alterations and modifications within the scope of the claims may be resorted to when desired.

In the drawings,

Figure 1 is a diagrammatic top plan view of a typewriting machine equipped with 70 the improved attachment.

Fig. 2 is a diagrammatic side view of the same.

Fig. 3 is a side elevation on a larger scale showing a portion of a typewriting machine 75 and a portion of the attachment.

Fig. 4 is a side elevation also on a larger scale of the forward portion of the attachment.

Fig. 5 is a sectional view, enlarged, taken 80 on the line 5—5 in Fig. 1, and illustrating the mechanism for actuating the typewriter keys.

Fig. 6 is a view similar to Fig. 5, showing the parts in a different position.

Fig. 7 is a transverse sectional detail, view taken on the line 7—7 in Fig. 5.

Fig. 8 is a detail plan view of the means for actuating the shift key of the typewriter.

Fig. 9 is a detail side view of the same.

Corresponding parts in the several figures are denoted by like characters of reference.

A typewriting machine A of conventional construction has been shown mounted on a base B which also supports the improved operating attachment as well as the motor C for actuating the driven parts, said motor being preferably an electric motor of any desired type which is supplied by a feed wire D and which includes a main driven shaft E and a counter shaft F from which motion is transmitted through intermeshing gears G to the main driven shaft 15 which may thus be constantly driven, said shaft

being supported in bearings 16. The shaft 15 carries at its forward end a pinion 17 meshing with a bevel gear 18 on a transversely disposed counter shaft 19 which will 5 thus be constantly driven when the motor is in operation. The counter shaft 19 is supported for rotation in the casing 20 of the improved attachment. The casing 20 is provided at its forward end with a key- 10 board, the keys of which, 21, correspond with the keys 22 of the typewriting machine A, being arranged in the customary manner in tiers or banks.

Each key 21 is mounted on the forward 15 end of a lever 23 fulcrumed on a shaft 24 that extends transversely through the casing, each lever having at its rearward end an upwardly extending arm 25 provided with a tooth 26. The casing 20 has a housing or magazine 27 in which a plurality of rods 28 are supported for vertical slidable movement, there being one such rod for each character key of the machine. Anti-friction bearings 29 are provided for the rods in 20 order to reduce friction and wear, and each of the rods 28 is actuated in a downward direction by means of a spring 30. The magazine 27 has a removable cap or top piece 31 to afford access to the interior for 25 the purpose of cleaning and lubricating the parts when needed. Each rod 28 has a notch 32 engaged by the tooth 26 of the arm 25 extending upwardly from one of the levers 23, said levers being actuated in an upward 30 direction by means of springs 33 arranged underneath, and the rods 28 being thus supported in normal or initial position; that is to say, the rods 28 will be normally supported by the interengaging teeth 26 and 35 notches 32, said teeth being normally held in engagement with the notches by the springs 33, whereby the levers 23 are actuated. Each rod 28 carries at its lower end 40 an eccentric wheel or disk 34, the pivotal supports of said eccentric disks or cams being located in the vertical plane of the axis of the shaft 19, the latter being equipped with a roller 35 which is normally driven in the direction indicated by the arrow a. 45 Each rod 28 is provided with a spring 36 having a struck up lug or detent 37 that normally engages a beveled notch 38 in the disk or cam 34 which will thereby be supported normally with the major part of its body in a raised position with respect to the pivot member 39 by which it is mounted upon or connected with the rod 28, said 50 spring detent serving also to arrest or stop the rotation of the cam member at the proper time when said cam member has been set in motion, as will be presently described.

It will be seen that by depressing the key 21 of one of the levers 23 the tooth 26 will be disengaged from the notch 32, causing

the rod 28 to be depressed, partly by gravity and partly by the action of the spring 30, thereby pressing the cam member 34 in engagement with the roller 35, by the rotation of which the cam member will be rotated about the axis of the pivot member 39, the power imparted by the frictional engagement of the cam member 34 with the roller 35 being sufficient to disengage the spring detent 37 from the notch 28. If the key 21 is released immediately 75 after being depressed, the lever 23 will be actuated by the spring 33 to move the tooth 26 in the path of the notch 32. The rotation of the cam member 34 will thus result in first moving the rod 28 upward against the tension of the spring 30 and then permitting the rod to be lowered by the tension of said spring until such downward movement is arrested by the tooth 26 engaging the notch 32; the impetus received 85 by the cam 34 through engagement with the roller 35 being sufficient to continue the motion of the cam until such motion is stopped by engagement of the spring detent 37 with the notch 38. If, however, 90 the key 21 is maintained in a depressed condition, the reciprocatory motion of the rod 28 will continue until stopped by the release of the key, because until such release is effected the cam member 34 will 95 be held in engagement with the roller 35 by the action of the spring 30, and the force exerted being sufficient to overcome the frictional resistance of the spring detent 37.

Each rod 28 has a laterally extending arm 100 40 with which is operatively connected one arm of a lever 41, the other arm of which carries a spring 42 through which is threaded a set screw 43 engaging the typewriter key 22 which corresponds to the attachment key 21, associated with the lever whereby the rod 28 is released, there being a rod 28 and a lever 41 for each character key of the typewriter and the attachment. The keys 41 are fulcrumed on shafts 44 lying in different planes to support the respective levers 41 in the most convenient positions relatively to the typewriter keys that are to be actuated thereby. The spring 42 of each lever 41 is bent so that the terminal portion of said spring will be depressed beneath the point of the set screw 43, and it will be readily understood that by proper adjustment of the set screw the impact or pressure of the lever on the typewriter key may be varied, according to whether a hard or a relatively soft blow is required. It will thus be seen that in a machine used for heavy work and where much manifolding is required, it will be 115 possible to adjust the mechanism so that the keys will be struck relatively hard, while when ordinary work not requiring 120 125

much manifolding is required the force or impact of the blows may be modulated. In like manner it will be seen that the keys of small sharp letters and of punctuation marks may be arranged to receive blows of less force than those of the large letters, so as to avoid puncturing of the paper.

Pivottally supported, as at 45, on the frame of the typewriter A, or in any convenient location, is a lever 46 adjacent to one end of which a drum 47 is supported for rotation, said drum having a spur wheel 48 connected therewith. The end of the lever 46 which carries the drum 47 has a notch 49 normally engaged by a tooth 50 formed on one arm of a bell crank lever 51 which is fulcrumed at 52, and the other arm of which is actuated by a spring 53, the tension of which serves to maintain the tooth 50 in engagement with the notch 49, thereby supporting the drum carrying end of the lever 46 in its normal position. The lever 46 is located above and in substantially parallel relation to the constantly driven shaft 15, and the last mentioned shaft carries a spur wheel 54 located directly below the spur wheel 48 of the drum 47 and capable of meshing therewith. A flexible element, such as a cord 55, one end of which is connected with and wound upon the drum 47, is guided under a guide pulley 56 which is located below the drum, and from thence the cord 55 is guided to the return lever 57 of the typewriter carriage 58, the cord being connected with the return lever, as shown. Suitable guide means are to be provided for the cord 55, one such being shown as consisting of a pulley 56. A bell crank 58 fulcrumed at 60 has one arm extended in the path of the typewriter carriage, the other arm of said bell crank being connected by a link or rod 61 with the arm of the lever 46 opposite to that which carries the drum 47.

The tooth carrying arm of the bell crank 51 is connected by a rod 62 with a lever 63 which is fulcrumed at 64 on the keyboard casing of the attachment. The lever 63 has been shown as extending slightly above the keys 21 to a convenient position for being manipulated by the operator, and said lever may be equipped with a pressure button 65 to enable it to be actuated by pressure exerted obliquely in a downward direction. It will be seen that by actuating this lever the bell crank 51 may be rocked to disengage the tooth 50 from the notch 49, thus permitting the arm of the lever 46 carrying the drum 47 to gravitate downwardly until the spur wheel 48 meshes with the constantly driven spur wheel 54. The cord 55 being thus placed under tension will exert a downward stress on the drum 47, whereby the spur wheels 48 and 54 will be maintained in engaging position, this being due to the

fact that the cord is guided beneath the pulley 56. The winding of the cord on the pulley will tension the said cord to actuate the return lever of the carriage which will now be returned to its starting point. As the carriage returns it strikes the bell crank 59, rocking the same and through it and the connecting rod 61 the lever 46 which is thus restored to its initial position, the catch 49 being engaged by the tooth 50 of the spring actuated bell crank 51 which is released as soon as the operator releases the lever 63. It is obvious that as soon as the carriage moves out of engagement with the bell crank 59, the operation may be repeated, irrespective of the precise location of the carriage on its track.

It is desirable that the keys should be locked against possibility of movement while the carriage is being returned, and in order that this may be effected there is provided for each rod 28 a toothed catch member 66, said catch members being pivotally mounted on a transversely disposed rod 67, and said catch members being connected in series by a transverse connecting rod 68. Each catch member is adapted to engage a notch 69 in the rod 28 with which it is associated, but the catch members are balanced in such a way that they will gravitationally swing clear of the notches 69, said catch members being thus normally idle. The operating rod 68 is terminally connected by a rod or link 70 with the lever 63 so that by the operation of said lever to disengage the toothed arm of the bell crank 51 from the notch 49 of the lever 46, the catch members 66 will be simultaneously actuated or thrown into engagement with the notches 69 of the respective rods 28, said rods being thus positively locked against the possibility of downward movement. As soon as the lever 63 is released the parts will be restored to normal or initial position.

For the purpose of actuating the shift keys of the typewriter special means are required owing to the fact that the shift keys are located at a distance from the keyboard of the attachment. The shift key 71 of the typewriter is actuated or depressed by one arm of a lever 72 fulcrumed at 73 the other arm of which is connected with and actuated by one arm of a lever 74 fulcrumed at 75, and the other arm of which carries the pressure button 76. The levers 72 and 74 are fulcrumed exteriorly on the side wall of the attachment casing 20, and said levers are terminally bent, as shown at 77, 78, the bent end 77 engaging the pressure button of the shift key 71, while the bent end 78 carries the pressure button 76.

From the foregoing description, taken in connection with the drawings hereto annexed, the operation and advantages of this

invention will be readily understood. By the use of the improved device or attachment speed may be gained, and the strength of the operator may be conserved since but very slight effort is required to depress the keys 21 and 65 whereby the mechanism is set in motion that actuates the keys of the typewriter as well as the carriage to effect the return movement of the latter. The actual power required for these operations is provided by the motor C, and by the means herein described, the power for actuating the typewriter keys may be modulated or varied.

15 The casing of the improved device or attachment has been shown as being equipped with a detachable cover member 79 which may be secured by fastening members 80 in such fashion as to permit its ready removal to afford access to the mechanism contained in the casing.

Having thus described the invention, what is claimed as new, is:—

1. In a device of the class described, a rod supported for vertical reciprocation, a key actuating lever operatively connected with said rod, an eccentric disk pivotally connected with the rod, and a constantly rotating roller adapted to engage the disk to produce reciprocatory motion of the rod.
2. In a device of the class described, a rod supported for vertical reciprocation, a key actuating lever operatively connected with said rod, an eccentric disk pivotally connected with the rod, and a constantly rotating roller adapted to engage the disk to produce reciprocatory motion of the rod; and spring means whereby the rod carrying the eccentric disk is forced in the direction of the constantly rotating roller.
3. In a device of the class described, a rod supported for vertical reciprocation, a key actuating lever operatively connected with said rod, an eccentric disk pivotally connected with the rod, and a constantly rotating roller adapted to engage the disk to produce reciprocatory motion of the rod; and spring means whereby the rod carrying the eccentric disk is forced in the direction of the constantly rotating roller; in combination with key actuated supporting means whereby the disk carrying rod may be normally supported intermediate the limits of its reciprocatory movement.
- 55 4. In a device of the class described, a rod supported for vertical reciprocation, a key actuating lever operatively connected with said rod, an eccentric disk pivotally connected with the rod, and a constantly rotating roller adapted to engage the disk to produce reciprocatory motion of the rod; and spring means whereby the rod carrying the eccentric disk is forced in the direction of the constantly rotating roller; in com-

bination with key actuated supporting means whereby the disk carrying rod may be normally supported intermediate the limits of its reciprocatory movement; and means whereby the eccentric disk may be supported against rotation.

5. In a device of the class described, a rod supported for vertical reciprocation, a key actuating lever operatively connected with said rod, an eccentric disk or cam pivotally connected with the rod, said disk having an inclined notch, and a spring detent carried by the rod and adapted for engagement with said notch to obstruct rotation of the disk.

6. In a device of the class described, a rod supported for vertical reciprocation, a key actuating lever operatively connected with said rod, an eccentric disk or cam pivotally connected with the rod, said disk having an inclined notch, and a spring detent carried by the rod and adapted for engagement with said notch to obstruct rotation of the disk, in combination with a constantly rotating roller and spring means whereby the disk carrying rod may be forced in the direction of said roller.

7. In a device of the class described, a rod supported for vertical reciprocation, a key actuating lever operatively connected with said rod, an eccentric disk or cam pivotally connected with the rod, said disk having an inclined notch, and a spring detent carried by the rod and adapted for engagement with said notch to obstruct rotation of the disk, in combination with a constantly rotating roller and spring means whereby the disk carrying rod may be forced in the direction of said roller; and key actuated means whereby the disk carrying rod may be normally supported intermediate the limits of its movement.

8. In a device of the class described, a rod supported for vertical reciprocation, an eccentric disk or cam pivotally connected therewith, a constantly rotating roller adapted to be engaged by the disk to produce reciprocatory motion of the rod, and a spring detent carried by the rod to engage the disk and to obstruct rotation thereof, said rod having a notch; and a key actuating lever operatively connected with the reciprocatory rod; in combination with a releasing key consisting of a lever having an arm provided with a tooth to engage the notch in the reciprocatory rod, and a spring whereby the key lever is actuated to maintain the tooth in engagement with the notch.

9. In a typewriter operating device, a key actuating lever, and operating mechanism for the same including a reciprocatory rod operatively connected with the lever, an eccentric disk pivotally connected with the rod, a spring detent engaging the disk, a constantly driven roller arranged in the

path of the reciprocating rod and adapted to engage the eccentric disk, a spring forcing the rod in the direction of the roller, and a spring actuated release key having a toothed arm engaging the reciprocating rod to obstruct movement of the latter in the direction of the roller.

In testimony whereof I affix my signature in presence of two witnesses.
